W. BAYLEY.

WINDOW SASH.

APPLICATION FILED JULY 20, 1914.

1,258,300.

Patented Mar. 5, 1918.

William Bayley
J. P. Walker, Attorney

UNITED STATES PATENT OFFICE.

WILLIAM BAYLEY, OF SPRINGFIELD, OHIO.

WINDOW-SASH.

1,258,300.

Specification of Letters Patent. Patented Mar. 5, 1918.

Application filed July 20, 1914. Serial No. 851,981.

To all whom it may concern:

Be it known that I, WILLIAM BAYLEY, a citizen of the United States, residing at Springfield, in the county of Clark and State of Ohio, have invented certain new and useful Improvements in Window-Sashes, of which the following is a specification.

My invention relates to window sashes and particularly to means for securing the panes of glass in place. The present invention is designed as an improvement upon the construction shown in Patent No. 1,042,524, and also shown in my co-pending application Serial No. 772,597.

The object of the invention is to simplify the structure as well as the means and mode of operation of such devices whereby they will not only be cheap in construction but will be more efficient in use, easily and quickly applied, and unlikely to get out of repair.

With the above primary and other incidental objects in view as will appear more fully in the specification, the invention consists of the features of construction, the parts and combinations thereof, and the mode of operation or their equivalents as hereinafter described and set forth in the claims.

Referring to the drawing, Figure 1 is a perspective view of a portion of the window sash with sections of glass secured therein by the retaining devices forming the subject matter hereof. Fig. 2 is a detail sectional view of the sash and glass showing the fastening devices and spacing member in place. Fig. 3 is a perspective view of the bearing member, and Fig. 4 is a similar view of the spring member detached one from the other and from the sash. Fig. 5 is a perspective view of the spacing member employed for separating double glass. Fig. 6 is a perspective view of the bearing member and spring inter-engaged one with the other.

Figs. 7 and 8 are perspective views from opposite side of a modification of the bearing member, Fig. 9 is a perspective view of the bearing member shown in Figs. 7 and 8 in an inverted position illustrating the method of inter-engaging the spring member therewith.

Fig. 10 is two perspective views from opposite sides of a preferred form of the device. Fig. 11 is a further modification thereof.

Like parts are indicated by similar characters of reference throughout the several views.

It has been found in practice that neither the sash bars nor the panes of glass are true in the direction of their length and therefore do not conform one to the other. It is also found that the glasses are not cut uniformly to fit the openings in the sashes. The edge of the pane of glass will frequently be spaced such distance from the sash bar that the spring member when employed in the manner shown in the aforementioned patent and application for patent will not afford sufficient hold upon the glass and will sometimes become disengaged from the edge of the glass and be projected into the crevice between the glass and sash bar. When the glass and sash bars do not conform uniformly one to the other, the spring member, as described in the former patent and application for patent, engaging the glass at an unsupported point subjects the glass to undue strain and may cause the breakage thereof.

To obviate these difficulties a bearing member of peculiar construction is provided to be interposed between the spring and the glass whereby the strain will be distributed throughout an extended area thereby reducing the pressure at the point of engagement of the spring and minimizing the liability of the device to cause the fracture of the glass.

The bearing member having extended bearings upon both the glass and the sash bar and being of sufficient height to compensate for any irregularity in the cutting of the glass, will not have a tendency to be tilted or tipped out of engagement with the glass or to pass into the recess between the glass and the sash bar.

While the device herein described becomes a permanent fastening and is embedded in the putty or cement by which the window is sealed, its primary object is to secure the panes of glass in place during the sealing operation somewhat in the manner that glazier's points are used with wooden sash and afterward embedded in the putty. The device forming the subject matter hereof is applicable to either wood or metallic sashes.

In the drawing 1-1 are sash bars of a metallic sash arranged angularly one to the other. They are substantially T shaped in cross section, the oppositely disposed flanges

of which form the ledges against which the glass is secured.

In the upper section of the sash portion shown in Fig. 1 there is shown a double glass comprising two panes of glass 3—3 spaced apart by intermediate spacing members 4. These spacing members 4 are of a substantially inverted U shape, the extremities of the arms of such U shaped members 10 being bent outward as at 5, in opposite direction and in a common plane. The ends of the extensions 5 of the spacing member extend across the edge of the glass while the intermediate U shaped portion projects 15 between the adjacent faces of the panes of glass to separate them one from the other.

It is in connection with double glazed sashes in which the inner pane of glass is supported only at spaced intervals by the 20 intermediate spacing member 4 that the present fastening device is found most advantageous. The use of the spring as shown in the said patent and application for patent with a double glazed sash at points intermediate the spacing members 4 subjects the inner glass to undue pressure at unsupported points which may cause breakage of the glass. The use of the bearing member however distributes this pressure to such 25 an extent that the fastening members may be used at various points throughout the length of the glass regardless of the location of the intermediate spacing members 4.

The bearing member is of such nature 35 that variations readily suggest themselves to a person skilled in the art and the device is capable of numerous modifications and variations. In the drawing five different forms have been shown.

40 Referring particularly to Fig. 3 the device comprises an angle bar 6 having transverse bearings 7 extending in opposite directions from the angular flange. In this particular form of the device the angle bar 45 has been slotted transversely adjacent to its end and the tongues formed by such slots bend into a plane common with the unslotted flange of the angle bar to form a transverse bearing member 7. The unslotted flange 8 of the angle bar is then 50 bent slightly downward adjacent to its ends, or arched as at 9, to provide beneath the flange 8 clearance sufficient for the bight of the U shaped spring 10. The spring 10 55 is constructed similar to the spring described in the aforementioned patent and application for patent and comprises a U shaped resilient member the extremities of the arms of which are bent at right angles 60 in opposite directions and perpendicularly to the plane of the bight.

In applying the device shown in Fig. 3 and Fig. 4 to the window sash the arched flange 8 of the angle bar is inserted in the 65 crevice between the glass and the web of

the sash bar with the tongues or bearing extensions 7 resting upon the web of the sash bar and the edge of the glass resting against the flange 8. In which position the perpendicular flange of the bearing member will bear upon the face of the glass in parallel relation therewith. The bight of the spring member 10 is then inserted in the clearance space beneath the flange 8 with one of the right angle extensions 11 75 of the spring member bearing against the outer side of the perpendicular flange of the bearing member and the opposite right angle extension 11 of the spring member engaged in a hole 12 in the sash bar. The 80 spring member 10 is of such proportion and the hole 12 so located that the spring member when engaged therewith is maintained under tension. This is an economical form of device, cheaply constructed and easily 85 applied and has been found to be quite efficient.

However for greater convenience in applying the devices and to facilitate the rapidity with which the glass may be secured 90 in position, it has been found desirable to connect the spring members 10 and the bearing members one to the other in position for quick and ready engagement with the sash. To this end the flange 8 which 95 projects between the glass and the sash bar is slotted to form a tongue 13, as shown in Fig. 6, which is extended beneath the arm of the spring member to secure the spring member in place in relation with the bearing member. 100

This binding tongue 13 may be provided in the form of device shown in Fig. 3 as well as in the form shown in Fig. 6 which differs from Fig. 3 only in the fact that the 105 bearing extensions 7, at each end, are bent to position angular one with the other and with the lateral flange 8, to obviate the necessity for arching the flange 8, as indicated at 9 in Fig. 3. 110

The angular position of the extensions 7 raises the bearing member above the sash bar sufficiently to provide clearance beneath the flange 8 to accommodate the spring member 10. Thus the device shown in Fig. 115 6 contains all the essentials, and differs only from Fig. 3 in the details of construction.

Viewed from the end, these bearing members may be said to be substantially T shaped and are applied to the sash with the 120 T shaped head resting upon the sash bar with one arm thereof projecting between the sash bar and the glass and the upright extending from the T shaped member bearing against the face of the glass where it 125 is held by the spring member 10.

In the event that the glass fits comparatively close to the sash bar a simple angle bar of sufficient length may be employed. It has been found however that when the 130

- space between the edge of the glass and the sash bar is of considerable extent and the spring member bears upon the bearing member in a plane beyond the edge of the glass there is a tendency for the bearing member to tip which is resisted by the bearing extensions 7 extending beyond the perpendicular of the flange in a direction away from the glass.
- 5 In Figs. 7 and 8 there is shown a modification of the bearing member comprising an angle bar having a lateral flange 14 and a perpendicular flange 15 bent upon itself as at 16 and then bent backward at right angles to the perpendicular flange 15 to form a lateral flange 17 located in a plane somewhat above the first mentioned lateral flange 14. The lateral flange 17 is slotted at each end and the slotted portions thereof are bent 10 downward as at 18, to bear upon the sash bar in a plane coincident with the first mentioned lateral flange 14. When applying this form of device to the sash the last mentioned flange 17 is inserted intermediate the 15 edge of the glass and the sash bar with the perpendicular flange portion 15 bearing against the face of the glass and the lateral flange 14 resting upon the sash bar but extending outward or in the direction away 20 from the glass. The downturned ends 18 of the flange 17 support the bearing member and prevent the tipping movement thereof, and together with the elevation of the flange 17 above the plane of the flange 14 25 afford clearance for the bight of the spring member 10. In the perpendicular portion 15 of this form of device are provided two holes 19 and 20. The spring member 10 is engaged with the bearing member by being passed 30 through one of the holes in one direction and then returned through the other hole whereby the upturned extremity 11 of the spring member will bear upon the outer face of the perpendicular flange 15 adjacent to the hole 35 20 while the other arm of the spring member will extend across the top of the lateral flange 14 and will have its downward extremity engaged in the hole 12 in the sash bar. This construction is clearly shown at 40 the right in Fig. 1. The forms of device shown at the left in Fig. 1 correspond to Figs. 6 and 10.
- To interengage the spring member 10 with the form of bearing member shown in Figs. 45 7 and 8 one end of the spring member is inserted through the hole 19 as shown by dotted lines at *a*, Fig. 9. After having one end inserted in hole 19 the spring member is turned downward to a position substantially in common plane with the lateral flange 14 as shown by dot and dash lines at *b*. In this position the other end of the spring member is inserted in the hole 20. The edge of the flange 14 adjacent to the hole 20 is notched 50 as at 21 to facilitate the insertion of the
- spring member 10. The first inserted arm of the spring member is then pushed through the hole 19 to the position shown by solid lines in Fig. 9. This assembles the bearing member and spring in position to be applied 55 to the sash.
- After the panes of glass are secured in position by means of the fastening devices heretofore described, putty or cement is applied as indicated at 22, Fig. 1, in which the 60 fastening devices are embedded. In the lower portion of Fig. 1 the application of the fastening members to a single pane of glass is illustrated.
- In Fig. 10 is shown a further modification 65 of the device, which, because of its simplicity, economy in manufacture, ease of application, and efficiency, will probably be found to be the most preferable form. This form of device consists of a simple angle bar comprising a flange or base 22 and a perpendicular flange 23 having at their juncture an open bead or rib projecting on the other side of the angle. In applying this form of device the bead or rib 24 is introduced between 70 the edge of the glass and the sash bar with the horizontal or base flange 22 resting upon the sash bar and the perpendicular flange 23 bearing upon the face of the glass. The bearing bar is secured by a spring member, as before described, the upturned end 11 75 of which bears upon the inner side of the perpendicular flange 23 of the angle while the opposite end of the spring member is engaged in the hole 12 in the sash bar. One 80 arm of the bight 10 of the spring member engages within the groove or recess formed by the open bead or rib 24, as shown in Fig. 10, and at the bottom in Fig. 1.
- In Fig. 11 is shown a modified form of 85 the device consisting of a simple angle bar comprising a base flange 25 adapted to rest upon the sash bar and a perpendicular flange 26 to engage the face of the glass. Adjacent to each end, the perpendicular 90 flange 26 is perforated to form integral tongues 27 which are bent outward beyond the plane of the flange 26 to support the glass. At a point substantially mid length of the flange 26 is an additional perforation, 95 the material removed from which forms a tongue 28. The resilient or spring member 10 is interlocked with the bearing member by being passed through one of the end perforations adjacent to the tongue 27 100 and thence returned through the central perforation whereby the upturned end 11 of the member will engage the face of the perpendicular flange 26 inside the angle. The tongue 28 is bent down upon the spring 105 member to clamp the latter in place. In applying the device, the tongues 27 are inserted intermediate the edge of the glass and the sash bar with the flange 25 engaging 110 the sash bar and the perpendicular 115
- 120
- 125
- 130

flange 26 engaging the face of the glass whereupon the opposite end of the spring member is engaged in a hole 12 conveniently located in the sash bar. In this position the 5 edge of the glass rests upon the tongues 27 and 28.

One of the primary objects of attaching the spring member to the bearing bar, as illustrated in Figs. 6, 9, and 11, is to insure 10 the application of the spring at the center of the bar, thereby causing an equal distribution of the pressure throughout the length of the bar.

The ends 7 of the bearing bars, shown in 15 Figs. 3 and 6, may be made flexible or resilient whereby they may be placed under tension when inserted intermediate the edge of the glass and the sash bar to insure a tight bearing upon both the glass and the 20 sash bar.

While several different forms of the device have been shown applied to a single structure in Fig. 1, it is to be understood that all these forms are not necessarily used 25 in a single window but that preferably only one form is used in a single construction.

From the above description it will be apparent that there is thus provided a device of the character described, possessing the 30 particular features of advantage before enumerated as desirable but which obviously is susceptible of modification in its form, proportion, detail construction or arrangement of parts, without departing from the 35 principle involved or sacrificing any of its advantages.

While in order to comply with the statute 40 the invention has been described in language more or less specific as to structural features, it is to be understood that the invention is not limited to any specific details, but that the means and construction herein described comprise but one mode of putting the invention into effect, and the invention 45 is therefore claimed broadly in any of its possible forms or modifications within the scope of the appended claims.

Having thus described my invention, I claim,

50 1. The combination with a window sash of retaining means for the sash glass comprising a bearing member engaging the face of the glass, a laterally disposed offset upon the bearing member serving to space the 55 edge of the glass away from the sash bar, and an arcuate spring member engaged with the sash and pressing said bearing member toward the glass, the bight of the spring being extended intermediate the edge of the 60 glass and the sash bar.

2. The combination with a window sash of retaining means for the sash glass com-

prising a rigid offset bearing member simultaneously engaging the face and edge of the glass, and an independent resilient spring member tending to press the bearing member into engagement with the glass. 65

3. The combination with a window sash of retaining means for the sash glass comprising a bearing member engaging the face 70 of the glass, a ledge thereon engaging the edge of the glass, and a foot portion engaging the sash, said ledge and foot portions being located in different planes, and a spring member tending to press the bearing 75 member upon the glass.

4. The combination with a window sash of retaining means for the sash glass comprising a bearing member having a laterally projecting portion supporting the glass in 80 spaced relation with the sash, and an arcuate spring member engaging the sash and bearing member, the bight of which is extended into the space intermediate the edge 85 of the glass and the sash.

5. The combination with a sash of a sash glass retainer including a bearing bar engaging the face of the glass, projections carried by said bar extending in opposite directions from the plane of the bearing bar 90 and an independent spring member yieldingly pressing the bearing bar into engagement with the glass.

6. The combination with a window sash of retaining means for the sash comprising 95 an angle bar having an arched base flange engaging the sash, the perpendicular flange of which engages the face of the glass, and a spring member tending to press the said angle bar toward the glass. 100

7. The combination with a sash of a retaining member for sash glasses comprising a bearing plate engaging the face of the sash glass having an arched base engaging the sash frame and an arcuate spring member engaging the bearing plate at one end and abutting upon the sash at its opposite end. 105

8. The combination with a window sash of retaining means for the sash glass comprising a bearing member engaging the face of the glass, a ledge upon the bearing member engaging the edge of the glass, an extension upon said member supporting the bearing member in spaced relation with the sash, and an arcuate spring bearing upon the said member, the bight of which projects beneath the said ledge. 110

In testimony whereof, I have hereunto set my hand this 30th day of June 1914.

WILLIAM BAYLEY.
